(57) **CLAIM**

The ornamental design for a dosing cup, as shown and described.

DESCRIPTION

FIG. 1 is a front perspective view of a first embodiment of a dosing cup embodying our new design;
FIG. 2 is a front elevation view of the dosing cup;
FIG. 3 is a left side elevation view of the dosing cup;
FIG. 4 is a rear elevation view of the dosing cup;
FIG. 5 is a right side elevation view of the dosing cup;
FIG. 6 is a top plan view of the dosing cup;
FIG. 7 is a bottom plan view of the dosing cup;
FIG. 8 is a front perspective view of a second embodiment of a dosing cup embodying our new design;
FIG. 9 is a front elevation view of the dosing cup;
FIG. 10 is a left side elevation view of the dosing cup;
FIG. 11 is a rear elevation view of the dosing cup;
FIG. 12 is a right side elevation view of the dosing cup;
FIG. 13 is a top view of the dosing cup; and,
FIG. 14 is a bottom view of the dosing cup.

Any broken lines shown in the drawings are for illustrative purposes only and form no part of the claimed design. Certain features currently not in broken lines may be placed into broken lines in other embodiments while other features in broken lines may be placed in solid lines in other embodiments.

1 Claim, 6 Drawing Sheets
